UNITED STATES PATENT OFFICE.

EDWARD McLARTY, SR., AND STANLEY L. BLANKENSHIP, OF LOS ANGELES,
CALIFORNIA.

UNIVERSAL RADIO AND DIRECT-SERVICE SYSTEM.

Application filed September 2, 1925. Serial No. 54,059.

This invention relates to a line delivery, signal service system for energizing remote loud-speakers, head-sets and similar signal instruments.

5 The invention has for an object to provide a system whereby radio broadcasted entertainment and other features, such as various news items, special and important Government warnings, notices and reports, and 10 other subject matter may be received at a central station and by it simultaneously sent over line apparatus to subscribers of a combined system having means adapted only for the receiving of signals and without 15 out return capacity.

An object is also to provide for the distribution, to the line subscribers of the system, of all desired programs and information which may be collected, by the central 20 station, from universal incoming telegraph and telephone line systems.

An object is to provide for the direct delivery of matter which is not received from outside sources, but is originated at it.

25 It is an object to provide a system capable of picking up or receiving local and far distant broadcasting stations so that any desired or the best entertaining program on the air can be carefully, clearly and efficiently taken up by the receiving central station of this system, by expert operators using the highest capacity and quality instruments, and by this station sent, over wire apparatus, to subscribers' loud-speakers, head-sets and other receivers; the purpose being to eliminate local detecting and amplifying equipment, and yet give perfectly tuned reception.

30 And an object is to provide a subscriber's key-lock controlled jack outlet and jack key-plug combination.

Therefore, an object is to provide a universal radio and direct wire line delivery service, which has but one receiving medium, 45 or radio detector, to deliver, by line wire, to key-lock controlled outlet to which speaking receivers are connectible by proper key plugs only, therefore enabling large and remote distribution to numerous individual 50 subscribers' receivers having but one common source of intake radio energy.

A great advantage of this is the elimination of individual and troublesome tuning, the initial cost and the upkeep expense of

private sets, the reduction of fire hazard 55 from and avoid the need of house aerials, which are generally so unsightly.

Further objects and advantages will be made perceptible in the ensuing specification of an embodiment of the invention as 60 exhibited in the related drawings; it being obvious and understood that this exposition is not intended to be limitary in character, but the usual reservation is here expressed of possible modification, variation and 65 adaptation of the invention within its spirit and scope as here claimed.

Figure 1 is a diagrammatic view of the general system.

Figure 2 is a detail view and diagram of 70 a key controlled jack-outlet, key-plug and loud speaker.

Fig. 3 is a detail of the key and lock switch.

In the present disclosure is shown a 75 broadcast wave receiving aerial 2 leading into a suitable detecting and amplifying set 3 with outlet lines 4 to a pair of fixed terminals 5 engageable by a suitable switch S, which can be thrown over to the circuit 80 6 of microphone transmitter T.

Terminals 7 of incoming telephone systems 8 are provided to be engaged by the switch S for sending purposes only to the present distributing system. 85

From the switch S run subscribers' service, trunk wires 9 which have numerous branches 10, to outlets, one or more of which may be located in rooms, halls or offices of the various subscribers' homes or institutions, such, 90 for instance, as places of amusement, dwellings, eating and drinking establishments, hospitals, etc.

Thus a community may be wired with the apparatus above described and as new 95 buildings are erected the service lines and outlets may be installed ready for future use by a potential subscriber.

To prevent surreptitious use of an installed service outlet these are provided 100 with appropriate key-lock jacks J to receive appropriate key-plugs P to which may be connected service wire W of any loud speaker L, or head set or the like. The lock, as diagrammatically indicated consists of the conventional pin and cylinder type; the cylinder having at its inner end contacts to be turned to engage the terminals 105

of the wires 10. The plug P includes the pin lifting cam shown in dotted lines in Fig. 2. When the key-plug is inserted in the cylinder the plug wires engage the contacts shown on the end of the cylinder. When the cylinder is unlocked and turned the circuit to lines 10 is completed.

It is understood that a suitable number of outlets O may be placed in various rooms 10 of a home or other building to allow use of a number of loud speakers at one time in the home, or permit carrying one loud speaker from room to room when so desired.

The central station is shown as having a 15 telegraphic receiving set 12, as a source of

information which can be translated and then transmitted by line to the service subscribers.

The station is equipped with a test speaker 15 to determine the quality of subscribers' 20 reception.

What is claimed is:

In a radio and telephone system, a line outlet device having fine terminals, a key lock including contacts coordinate to the 25 terminals, and a key-plug having conducting leads cooperating with the contacts to close a telephone receiver circuit.
